PHOTOLITHOGRAPHIC PRINTING ART

Mark A. Mattare, Aldie, Va.

Application June 8, 1951, Serial No. 230,560

5 Claims. (Cl. 41—46)

This invention relates to an improved method of applying various characters such as a word, legend, symbol, numeral, indicia or pattern to a negative for instance such as used in the lithographic printing art. The invention is more particularly applicable to the production of maps, charts and the like, and permits corrections and additions to be made directly on the negative plate without the use of photography which has been the common practice heretofore in making such additions or corrections to the master negative.

In the preparation of maps, for example, it is conventional practice to prepare a master copy showing the towns, rivers, lakes, roads and contours, and wherein the various names and legends are cut-out from opaque printed adhesive sheets and glued to the master copy at the proper location. The finished master copy is then photographed and a negative plate prepared therefrom for use in making offset or straight printing reproductions of the master copy. A proof is pulled on the proving press and this is sent to the proof reader for final checking before a sensitized metal printing plate is made for the press. Invariably, the proof reader finds changes and corrections to be made which usually involves the addition or changing of words, symbols or patterns on the master copy.

When changes are required to be made on the master copy as shown on the proof, the type compositor sets up the names, symbols or the like legends which are desired to be added to the master copy. Then a print or prints are pulled and sent to the photographer. After this is done, a specially prepared negative is made. For example, a wet print negative, containing the names or symbols to be added, is coated with a suitable stripping solution and, after drying, one or more applications of a collodion coating solution is broadcast over the negative. Thereafter, the negative is placed in acetic acid bath which permits the ready removal of the film containing the names, symbols or patterns which are to be placed on the wet negative print. The desired names or symbols are cut out of the film by the use of a sharp knife and transferred to the wet negative, the film portions being placed in a window or cleared-out space on the negative.

This prior method of making additions to the master negative, as described, is a very tedious as well as expensive method and requires the use of photographic equipment and necessitates working with a wet negative print. The method of the present invention, however, entirely eliminates the need of photography in making such changes on the master negative plate or film and either a wet or dry negative plate or film may be changed or corrected. Furthermore, in utilizing the improved method of this invention, such additions and changes can be made in a much shorter time and at substantially less expense to the lithographer.

The principal object of the present invention is to greatly simplify the method of making changes, correc-

2

tions or additions on a wet or dry master negative plate or film.

Another object of the invention is to provide a method of placing selected characters, as aforementioned, on a negative, such as commonly mounted on glass or a like transparent surface, without requiring the use of photography and making of a photographic negative of the characters to be applied to the master negative.

Still another object of the invention is to provide an inexpensive and simple method of making changes and corrections on a negative plate so that the work of highly skilled artisans is not required as well as eliminating the need for preparing an auxiliary photographic negative of the characters or legends to be added to the master negative.

Briefly, the method of the present invention comprises the following steps:

(1) The printing of the various names, symbols, numbers or other legends to be used on a transparent cellulose xanthate or viscose sheet, such as "cellophane," the transparent sheet being printed on both sides.

(2) Exposing the printed form in step (1) to a sensitized aluminum plate from which a print is pulled using ink which results in a negative print of the aforementioned names, symbols, etc.

(3) Coating the negative print thus formed with adhesive wax, and cutting out the desired name or symbol to be inserted on the master negative and placing the cut-out legend directly on the negative plate, being simply pressed against a window opening scratched or otherwise made on the negative at the desired location.

(4) After touching up any space left around the cut-out insertion on the master negative plate with opaque material, the corrected master negative is now ready to be printed to sensitized aluminum and the resultant plate transferred to the press.

Where the correction in the master negative plate, for example, involves a change in a pattern or printed lines, and which patterns or the like are commonly printed on a transparent flexible regenerated cellulose sheet such as "Zipotone," the cut-out portion of the cellulose sheet having the desired pattern is merely coated with the adhesive wax and applied directly to a window made in the master negative plate as described above in the case of a printed name or symbol.

The improved and simplified method of applying various characters to a lithographic negative plate is further illustrated in the accompanying drawing in which,

Figure 1 is a fragmentary view illustrating a portion of the printed map which has been prepared in accordance with this invention;

Figure 2 is a fragmentary view of a portion of a transparent cellulose xanthate sheet having printed thereon various legends for selective use in making additions on the master negative;

Figure 3 is a negative print of a portion of the printed cellulose sheet shown in Figure 2 and illustrated on an enlarged scale;

Figure 4 is a similar fragmentary portion of the negative print illustrated in Figure 3 after applying a coating of adhesive wax thereto and before application of the same to the back of a glass plate;

Figure 5 is a fragmentary view illustrating the removal of a legend portion from a negative print, such as shown in Figure 4, and illustrating the use of tweezers for separating the cut-out legend from the glass backing sheet;

Figure 6 is a fragmentary detail view in enlarged scale showing a portion of the master negative plate as disposed on a glass sheet, and illustrating the manner of removing the portion of the negative to form a window in the same, and showing the cut-out legend positioned therein and adhesively secured in place; and

Figure 7 is a view in perspective of a portion of the lithographic master negative glass plate which is used to form the map, a portion of which is shown in Figure 1, the negative plate being illustrated on an enlarged scale from that of Figure 1, and showing how the legend "Flowing Well" and the pattern for a lake are added directly to the master negative plate in accordance with this invention.

Referring to the drawing in detail, particularly with reference to Figures 1 and 7, the numeral 10 represents a printed map prepared in accordance with this invention and showing a legend 12 and a lake pattern 14 which have been added directly to a photolithographic master negative 15 which is arranged on a glass plate 16. The steps required for adding the legend "Flowing Well" is graphically illustrated in Figures 2 through 6, and comprises printing of the legend 12 together with other legends or characters as desired on both sides of a thin, transparent, regenerated cellulose sheet 18 such as cellulose xanthate. This print is then formed into a negative print by exposing the same to a sensitized aluminum plate, the resultant negative being rolled up on a metal plate with regular "cellophane" ink to form a negative print film 20. The negative print film 20 preferably has a thickness of approximately one-thousandth of an inch.

After the thus prepared negative print film 20 is dry as by placing the same on a drying rack or blotter until the ink is dry, an adhesive wax coating 22 is applied thereto. Where offset printing is to be used, the adhesive coating is applied on the printing face and where straight printing is to be employed, the adhesive coating is applied on the opposite face as will be understood.

In the drawing, the lithographic master negative 15 is arranged on the glass backing 16 for offset printing and, accordingly, the negative film 20 is coated on its printed face with adhesive as indicated at 22 on the drawing. The wax adhesive composition which forms no part of this invention, generally consists of a suitable mixture of refined beeswax and latex rubber. The proportion of ingredients is such that the adhesive is made to hold the cut-outs by means of pressure only, the coating being preferably applied evenly over the surface of the negative print at a temperature between about 90° and 110° C. After coating the negative print film 20 carrying the desired characters with the adhesive wax coating, the print is applied to the back of a glass sheet 24 as illustrated in Figure 5 so as to conveniently hold the negative print material whereby the same can be readily cut out for transfer to the master negative plate.

When it is desired to correct the lithographic negative plate 15 so as to add a legend for example as indicated by the reference character 12, an instrument 25 having a sharp edged blade is used to cut out the legend from the negative print film as shown at 26 in Figure 5. A corner of the cut-out legend is conveniently raised by inserting the edge of the blade of the instrument 25 thereunder and grasping the raised corner by means of tweezers as illustrated at 28. In this manner, the cut-out printed negative legend 26 which is to be transferred to the master negative is removed from the glass backing sheet 24. Thereafter, the cut-out negative legend 26 is then transferred directly to a scratched out window 30 formed in the lithographic master negative plate 15, the cut-out being secured in place by pressing the same down firmly against the glass surface in the window of the master negative. The adhesive wax on the face of the legend portion serves to hold the same securely to the negative glass plate.

As shown in Figure 6, the window 30 in the negative 15 is suitably scratched or cut out by using the sharpened edge blade portion of the instrument 25. After applying the legend in the window, the open space 32 left around the legend 26 is filled with negative opaque. The thus corrected master negative plate 15, as illustrated in Figure 75

7, is then ready for printing to sensitized aluminum and installation of the resultant plate on the printing press.

Where a particular pattern or printed lines are desired to be placed on the master negative plate, such as commonly used to illustrate a lake, and wherein a printed pattern of the desired illustration is available on a transparent sheet such as "Zipotone," as aforementioned, the adhesive wax may be applied to the printed pattern and a cut-out portion of the desired size may, as illustrated at 34 in Figure 7, be merely pressed into place directly on the lithographic master negative plate 15. The wax adhesive applied thereto, as illustrated, on a turned-up portion in Figure 7 functions to firmly hold the same in place on the master negative plate.

It will, accordingly, be seen that by utilizing the present invention, various legends, words, numerals, patterns or character references may be readily applied directly to the master negative and without the use of photography and in a simple and easy manner.

Although the invention has been illustrated and described in connection with the preparation of a master negative on a glass plate for the reproduction of printed maps, it will be understood that the invention is not limited to this particular use. The invention, for example, 20 may be advantageously employed for making additions and corrections on similar negatives or their equivalents, the invention being limited only insofar as defined by the scope of the hereinafter appended claims.

What is claimed is:

30 1. A method of making an addition to a master negative from which a lithographic printing plate is to be produced, said method comprising providing a transparent master negative plate with indicia thereon and which indicia requires changes, ink printing a positive legend of said changes on a transparent strip, exposing the positive printed transparent strip to a sensitized plate to obtain a printing plate, pulling an ink impression in negative form on transparent material from the printing plate, forming a transparent area in the master negative plate at the position requiring said changes, and securing the transparent material carrying the pulled negative impression in the transparent area of the master negative plate.

2. The invention according to claim 1, wherein the positive legend is printed on both sides of the transparent strip.

3. The invention according to claim 1 with the additional step of masking with opaque coating material any uncovered portions of the transparent area showing around the applied material carrying the pulled negative impression.

4. The invention according to claim 1 wherein said sensitized plate is aluminum.

5. A method of making an addition to a master negative from which a lithographic printing plate is to be produced, said method comprising providing a transparent master negative plate with indicia thereon and which indicia requires changes, ink printing a positive legend of said changes on a transparent strip, exposing the positive printed transparent strip to a sensitized plate to obtain a printing plate, pulling an ink impression in negative form on transparent material from the printing plate, applying an adhesive wax coating to the transparent material carrying the pulled negative impression, 55 securing the last mentioned transparent material by the said adhesive wax to a glass plate and cutting out a portion of the transparent material carrying the desired pulled negative impression, forming a transparent area in the master negative plate at the position requiring said changes, and adhesively securing the said cut out portion of transparent material carrying the desired pulled negative impression in the transparent area of the master negative plate.
